UNITED STATES PATENT OFFICE.

HUGH E. POOL, OF RAINY, OKLAHOMA TERRITORY.

PROJECTILE FOR FIREARMS.

SPECIFICATION forming part of Letters Patent No. 670,728, dated March 26, 1901.

Application filed December 27, 1900. Serial No. 41,197. (No model.)

To all whom it may concern:

Be it known that I, HUGH E. POOL, a citizen of the United States, residing at Rainy, in the county of Washita and Territory of Oklahoma, 5 have invented certain new and useful Improvements in Projectiles for Firearms; and I do declare the following to be a full, clear, and exact description of the invention, such as will enable others skilled in the art to which 10 it appertains to make and use the same.

My invention relates to improvements in bullets or projectiles for firearms; and the object thereof is to provide a projectile which dispenses with the use of a cartridge-shell and 15 obviates the loss of time and inconvenience attendant upon discharging the same from the arm and which is also adapted to receive a plurality of impulses to increase its range and effectiveness.

With this and other minor objects in view 20 the invention consists of certain novel features of construction, combination, and arrangement of parts, as will be hereinafter more fully described, and particularly pointed out in the appended claims.

In the accompanying drawings, Figure 1 is a longitudinal sectional view of a projectile constructed in accordance with my invention. Fig. 2 is a detail perspective view of the fulminate-cap and its stem. Fig. 3 is a detail 30 sectional view of the same.

Referring now more particularly to the drawings, the numeral 1 designates my improved bullet or projectile, which is constructed of two sections 2 and 3, which for convenience of description I will term the "body" and "point" of the projectile. The body 2 in practice is to be made longer and heavier than the point 3 to adapt the projectile to 35 "carry" well and to also adapt the secondary charge of powder or other explosive to exert its full expansive force on the point-section, as hereinafter described. The point-section is provided at its rear end with a rabbet 4, which fits within and releasably connects it with the forward end of the body-section.

The body-section 2 is provided at its front and rear ends with chambers 5 and 6 to receive a primary and a secondary charge of 40 powder, and a longitudinal bore or passage 7 connecting said chambers. The charges 8 and 9 of powder contained within said cham-

bers may be and preferably are of the smokeless variety; but I may employ in lieu thereof any other kind of explosive or expansive gas 55 suitable for the purpose. A cap or receptacle 10 to receive a charge of fulminate is arranged within the primary-charge chamber 5 and is provided with one or more openings 11, communicating with said chamber, and a tubular 60 stem 12, said stem being in open communication with the cap and bore 7 and fitting within the latter to hold said cap supported concentrically in the axial line of chamber 5. Through this tube and through the bore or passage 7 extends a time-fuse 13, which is ignited by the fulminate to fire the secondary charge 9.

In operation after the projectile has been placed within the barrel of the firearm the 70 primary charge 8 is fired in the usual manner by the firing-pin striking the cap 10 and exploding the fulminate therein, whereby the projectile is sped from the arm. At the same time the fuse 13 is ignited and in a predetermined time fires the secondary charge 9, 75 whereby the point 3 of the projectile is discharged from the body 1 and is caused to traverse a greater distance. By this construction and mode of operation it will thus 80 be seen that I attain the twofold advantage of dispensing with the usual cartridge-shell and securing greater range of the projectile, whereby valuable time in loading is saved and the effectiveness of the projectile materially increased.

Changes in the form, proportion, and minor details of construction may be made within the scope of the invention without departing from the spirit or sacrificing any of the advantages thereof.

Having thus fully described my invention, what I claim as new and useful, and desire to secure by Letters Patent of the United States, is—

1. A projectile for firearms, comprising a body-section having primary and secondary explosive-charge chambers, a point-section releasably connected with said body-section and adapted to be projected therefrom by 100 said secondary charge, and means for successively firing said charges, substantially as set forth.

2. A projectile for firearms, comprising a

body-section having at its opposite ends primary and secondary explosive chambers and a passage between said chambers, a point-section releasably connected with said body-section and adapted to be projected therefrom by the secondary charge, a fulminate-cap within the primary chamber and having a tubular stem within said bore, and a fuse extending through the bore and stem and con-

necting said chambers, substantially as set forth.

In testimony whereof I have hereunto set my hand in presence of two subscribing witnesses.
